AIR HUMIDIFIER FOR INTERNAL COMBUSTION ENGINES

William G. Hardt, Chicago, Ill.

Application June 4, 1938, Serial No. 211,762

8 Claims. (Cl. 261—107)

This invention relates to a novel and improved air humidifier for internal combustion engines.

One of the objects of this invention is to provide a novel and improved humidifier for properly moistening the air in passing from the air cleaner to the carburetor of an internal combustion engine, to effect economy in the use of the fuel.

Another object of this invention is to provide an improved humidifier whereby a slight amount of water or similar liquid is added to the fuel mixture in the form of a finely divided and rarified spray, so as to increase the moisture content in the fuel mixture to the greatest and most efficient degree and produce a more complete and economical combustion of the fuel.

Another object of this invention is to provide such a humidifier which is provided with means to shut off the water supply automatically when the fuel supply is shut off or when the engine idles, in order that the moisture distributing means can become dry, to avoid rotting, when the engine is not in use.

These and various other objects and advantages are attained with this invention, as will become apparent from the following description, taken in connection with the accompanying drawing wherein the invention is shown in its preferred form; it being understood that various other arrangements and form of construction may be adopted in carrying out the objects and purposes of this invention.

In the drawing:

Fig. 1 is an elevational view, illustrating this invention diagrammatically as applied to the connecting portion between the air cleaner and the carburetor of an internal combustion engine, with the liquid control valve automatically operated by the operation of the throttle valve.

Fig. 2 is an enlarged vertical sectional view taken centrally thru the humidifier.

Fig. 3 is in part a plan and in part a sectional view of the humidifier, taken along line 3—3 of Fig. 2.

The humidifier or air moistener which is disclosed in this application is shown as applied to the connecting portion between the carburetor 5 and the air cleaner 6 of an internal combustion engine, for example of an automobile. It is preferably arranged to be mounted upon the air intake neck 7 of the carburetor 5, being located within the neck 8 of the silencer portion 9 of the air cleaner 6, which surrounds said neck 7. A split metal band 10 may be used to secure these parts together.

The form of construction illustrated in the drawing comprises a casing 11 which is shown substantially ring-like or cylindrical, including an inner wall 12 and an outer wall 13 spaced apart to provide an annular well 14 between said walls for containing liquid, and providing an inner air channel or shaft 15 within the inner wall 12. Said liquid is supplied to the well thru an inlet tube or conduit 16 which is secured to a mouth 17 on the casing and extends from a tank or reservoir 18 containing the liquid, such as water.

Moisture distributing means or permeable means 20 is mounted across the air channel 15 in the casing, and this means is preferably in the form of fabric sheet means and includes a 15 plurality of fabric members or diaphragms, three such members, 21, 22 and 23, being shown in this form of humidifier illustrated. These members may be of gradually varying fineness and permeability to better distribute or rarify the 20 liquid particles into a fine spray.

Spacing means or elements are used to retain the fabric members properly spaced. These elements include rings or washers 24, which may be of closely grained cork, or other slightly compressible and non-porous material, said rings being placed between the outer marginal parts of the fabric diaphragms and are supported on the inner wall 12, in such a manner that the edges of the fabric diaphragms project beyond said 30 rings into the well 14, to absorb liquid therefrom and admit it to their central portions. Other spacing elements 25 are also placed between the intermediate parts of the diaphragms to keep the latter evenly spaced apart, and these elements 35 are preferably in the form of cords extending thru the diaphragms and each having a knot 26 tied therein between each two adjacent diaphragms, to serve for spacing the intermediate parts of the latter, as best shown in Fig. 2.

Means is also provided to secure the diaphragms and the spacing elements in place, and this includes a securing collar or annular nut 27 which has threads thereon engaged in threads on one of the casing walls, being preferably threaded to the outer wall 13 and covering the well 14. It has an upper annular wall 28 which bears on the spacing rings 24, to press them firmly together and clamp the fabric therebetween, and the inner edge 28' of wall 28 is preferably 50 beveled, to aid the silencer 9 in its silencing function. Notches 29 are provided in the securing nut 27, to receive the prongs of a tool in adjusting the nut on the casing for securing the fabric means 20 and the spacing rings in place; and 55

companion notches 38 are similarly provided in casing 11 for receiving similar prongs, to facilitate relative turning of threaded nut 27 on the threads of casing 11, to secure the parts firmly but adjustably together.

5 A guard screen 31 is preferably mounted in the lower part of the air shaft 15.

A control valve 32 is interposed in liquid conduit 16, and its lever 33 is connected by a rod 34 10 with the control lever 35 of the throttle valve, so that the liquid control valve 32 will be automatically operated by the operation of said throttle valve and its lever 35 thru the control rod 36 attached to said lever. By opening the throttle 15 valve the liquid control valve 32 will also be opened to the required extent, and when the throttle valve is closed or in idling position then valve 32 will also be closed, to shut off the liquid from the fabric sheet means and enable the latter 20 to dry out and avoid rotting.

The adjustable and removable securing nut 27 facilitates properly clamping the spacing rings 24 with the sheet means in place, and likewise facilitates the removal and replacement of said 25 sheet means whenever desired.

I claim:

1. A humidifier mountable in the connecting portion between a carburetor and an air cleaner of an internal combustion engine, said humidifier 30 comprising a casing fitting in said connecting portion and including an inner air channel and a well therearound for containing liquid, fabric means stretched across said air channel and having the end means extending into the well, and means removably and adjustably mounted on the casing for securing the fabric means firmly in place but permit removal thereof.

2. A humidifier mountable in the connecting portion between a carburetor and an air cleaner, 40 said humidifier comprising a tubular casing fitting in said portion and including spaced walls providing a liquid well between said walls also an air channel within the inner wall, fabric means stretched across said air channel and the inner wall and having the end means protruding into the well to absorb moisture therefrom, and securing means including means threaded on said casing for covering said well and for securing said fabric means firmly but adjustably in position.

50 3. A humidifier mountable in the connecting portion between a carburetor and an air cleaner carried thereon, said humidifier comprising a casing fitting in said portion and including an inner air channel and a liquid well around the same, a plurality of fabric sheet members

stretched across said channel and having the ends extending into the well, means between the fabric members for spacing them, and means on the casing for securing the fabric members and spacing means in place.

5 4. The subject matter set forth in claim 3, wherein said securing means includes a nut threaded on the casing for adjustably and removably securing the fabric members and spacing means in position.

10 5. A humidifier adapted to be mounted on the neck of a carburetor having the neck of an air cleaner mounted around the same, said humidifier comprising a casing of rigid material fitting in said neck and including spaced walls providing a liquid well between the walls also an air channel within the inner wall, a plurality of fabric sheet members stretched across said air channel and having the ends extending into the well, annular non-porous means mounted between the 15 marginal portions of said fabric members for spacing them, means between the intermediate parts of said fabric members for retaining them properly spaced, and means on the casing for securing the fabric members and the spacing means 20 therebetween in place.

25 6. The subject matter set forth in claim 5, wherein said intermediate spacing means consists of cords extending thru the fabric members and having knots tied between each two adjacent 30 members.

35 7. The subject matter set forth in claim 5, wherein said annular spacing means consists of partly compressible spacing rings, and the securing member consists of a metal nut having threaded engagement with the outer wall of the casing and being arranged to cover the well and also to be adjustably fastened down on the spacing rings and the fabric members.

40 8. A humidifier mountable in the connecting neck portion between an air cleaner and a carburetor provided with a throttle valve, said humidifier comprising a casing fitting in said connecting portion and including an inner air channel and also a liquid well, fabric means stretched 45 across said air channel and having the end means extending into the well, means for securing the fabric means firmly in place, a valve equipped conduit on the casing for supplying liquid to the well, and means operatively connecting said liquid valve with the throttle valve, whereby the liquid valve will be automatically 50 opened and closed with the opening and closing of the throttle valve.

55 WILLIAM G. HARDT.
